DESIGN.

F. MANKEY.

MOLDING.

No. 16,527.

Patented Feb. 16, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,527, dated February 16, 1886.

Application filed November 13, 1885. Serial No. 182,754. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Upon the face of the molding appears a raised band, A, having serrated edges B and C, the serrations on edge B being opposite the indentations on edge C, and vice versa. Upon the face of the band A are diagonal grooves or channels D E, extending from the angles of the indentations on one edge to the angles of the indentations on the other edge of said band, and standing alternately in opposite direc-

tions. By these channels the face of the configuration appears to be divided into parallelograms or rectangular figures. In the center of each of these figures is a circular depression, F.

I claim—

The design a for molding, substantially as herein shown and described, which consists in the raised band A, having serrated edges B C, and on its face diagonally-disposed grooves or channels D E and circular depressions F.

FREDERICK MANKEY.
